UNITED STATES PATENT OFFICE.

JACOB REESE, OF PITTSBURG, PENNSYLVANIA.

MANUFACTURE OF INGOT IRON AND STEEL.

SPECIFICATION forming part of Letters Patent No. 267,717, dated November 21, 1882.

Application filed January 12, 1882. (No model.)

To all whom it may concern:

Be it known that I, JACOB REESE, a citizen of the United States, residing at Pittsburg, in the county of Allegheny and State of Pennsylvania, have invented a certain new and useful Improvement in the Manufacture of Ingot Iron and Steel Direct from the Blast-Furnace; and I do hereby declare the following to be a full, clear, and exact description thereof, reference being had to the accompanying drawings, in which—

Figure 1 on Plate 1 indicates a front elevation of a portion of my improved plant, showing a blast-furnace, regenerating hot-blast stoves, blast-connections, and gas-stack, together with two portable converters mounted on converter-trucks and a locomotive on a railway arranged in such a manner that the converters may be removed to and charged direct with the molten metal as it flows from the hearth of the blast-furnace and then conveyed back into the converting-house. Fig. 2 on Plate 2 indicates a front elevation of the portable converter and the converter-truck when run into position to deposit the trunnions of the converter into the trunnion-journals of the converter-frame, and a hydraulic ram for lowering the converter and converter-truck. It also indicates a side elevation of an improved apparatus for connecting and disconnecting the blast-conduit with the trunnion of the converter. Fig. 3 on Plate 3 indicates a side elevation of the portable converter, converter-truck, the adjustable section of railway between the standards of the converter-frame, and the hydraulic ram for elevating the railway-track to lift the converter onto the truck and out of its trunnion-bearings. The dotted lines represent the position of the track and ram when down. Fig. 4 on Plate 4 indicates a side elevation of the converter, with its blast-pipe leading from the trunnion down into the tuyere-box, showing its manner of removal to and from the blast-furnace on the converter-truck, which is provided with an iron frame of a suitable form to engage the back of the converter and hold it securely during transportation. Fig. 5 indicates a front elevation of the same. Fig. 6, Sheet 2, is a sectional view of the closed sleeve and blast-nozzle, showing their operation.

Like letters of reference indicate like parts wherever they occur.

Heretofore it has been the common practice to produce Bessemer steel by smelting the ores in the blast-furnace, running the metal into pigs, remelting the metal in a silicious-lined cupola, transferring it to the converter by a silicious-lined ladle or troughs, and then decarburizing, desiliconizing, deoxygenizing, and re-carburizing the metal. In the practice of that method the metal takes up a considerable amount of silica from the sand molds when cast at the blast-furnace, and when remelted takes up a portion of silica from the lining of the cupola, a portion from the ash of the fuel, and a portion from the lining of the ladle or troughs, and consequently a considerable amount of silicic acid is carried with the metal into the converter. The presence of this acid in the converter is highly objectional when steel is to be produced by the basic process, as silicic acid is very destructive to the lime lining, requires the presence of larger basic additions for its neutralization, and retards dephosphorization. Besides this defect, when metal is remelted for the use of the basic process another and a serious defect occurs—that is, that from forty to fifty per cent. of the carbon is eliminated, and there is a considerable loss of manganese in remelting.

My invention consists of an improved method of working the metal direct from the blast-furnace by running it into a portable converter mounted on a converter railway-truck, then conveying the converter into the converting-house, depositing it into the trunnion-journals of the converter-frame, forming the blast-connections, bessemerizing the metal in the usual manner, and, when the metal has been cast, disconnecting the blast-conduit and removing the converter to receive a fresh charge at the blast-furnace. My invention further consists in an improved construction and arrangement of apparatus adapted to the use of the said process.

The chief objects of the invention are to overcome the defects of the indirect method previously described, as applied to the basic process, and to secure greater economy and the production of a better quality of steel by the use of either the acid or basic process.

In order to secure these objects and to carry

out my method of treatment, I propose to do away with a portion of the present Bessemer plant, by discarding the cupolas for remelting the metal, the hoists for lifting the pig up to 5 the cupola, and the troughs for carrying the molten metal into the converters, and in place of such arrangements use a portable converter, a special converter-truck for carrying the converter, and a railway running from the blast-furnace to the converting-house at such an elevation and arrangement that the molten metal may be tapped direct into the converter, and when run into the converting-house the car and converter may be lowered down, by a hydraulic ram 10 or other suitable device, to bring the trunnions of the converter into their bearings in the converter-frame and to withdraw the truck when the converter is in position.

I shall now describe the construction and 15 arrangement of an improved apparatus adapted to the use of my invention, so that others skilled in the art to which it appertains may make and use the same.

In the drawings, A indicates an improved 20 blast-furnace plant, and a indicates a section of the railway connecting the furnace with the converting-house. This portion of the railway is arranged at such a relative plane with the furnace as to allow the molten metal to 25 flow direct into the mouth of the converters a', which are mounted on the converter-trucks a''. These converter-trucks a'' are provided with a frame of cast or wrought iron of a shape to 30 correspond with the shape of the back of the converters, so as to hold them securely without bringing any strain on the tuyere-box or the 35 blast-pipe leading from the trunnion into the tuyere-box, and thus avoid the necessity of clamping the converters to the trucks during 40 transportation.

a³ indicates a cap-piece to fit over the mouth of a converter as soon as charged, in order to 45 prevent the escape of caloric from the metal during its transportation from the furnace to the converting-house.

B indicates the locomotive used for conveying the trucks and converters into the converting-house.

In Sheets 2 and 3, c indicates an adjustable 50 section of the track a. This adjustable section communicates with the track a at the rear of the converter-frames, where it rests on a pivotal connection supported by boxes secured to upright frames, and the end of the 55 track a is also supported by brackets riveted to these frames. The forward part of the adjustable track-section c rests on a cross-plate, c', which is attached to the piston of a hydraulic ram, C, which is provided with trunnions c² and c³ which are mounted in the pillow-blocks c⁴ and c⁵, in order that the ram may 60 swing freely on its trunnions to cause the piston to always come into and remain in line with the direction in which the force is applied, 65 in order that lateral strains upon the piston may be avoided.

E (shown in Fig. 2) indicates an apparatus resting on the converter-frame. This blast-adjusting apparatus consists of a hydraulic ram or other suitable motor attached to the 70 end of a hollow blast-nozzle, e, which works in a close sleeve, e'. The forward part or end of this blast-nozzle e is beveled to secure a tight joint when the ram forces it forward into the beveled blast-opening of the converter-trunnion, and it is provided with a lateral slot or opening at the rear end of the bore, which is brought into line with a blast-opening, e², in the side of the sleeve when the blast-nozzle is forced forward, and forms the joint 80 with the converter-trunnion, thus admitting the blast into the nozzle, and through it into the converter-trunnion, so that it will be seen that the blast is automatically admitted into and excluded from the blast-nozzle, in its forward- 85 and -backward movement, in forming and detaching the blast-connection with the converter.

I have shown an apparatus for elevating and lowering the end of the adjustable track-section to bring the converter into its bearings on the converter-frame. This apparatus is especially adapted for this purpose; but I do not wish to confine myself to its use, as there are other mechanical devices for lifting 90 which may be applied, and will operate in a more or less perfect manner; nor do I wish to confine myself to any peculiar construction of converter, nor arrangement for disconnecting and connecting the blast-conduit from the 95 converter-trunnion, as it is evident that other devices may be used to carry out my method; but in practice it will be found that the particular construction shown and described may be more readily and quickly adjusted, and will 100 form a more perfect blast-connection with the trunnion than could be secured by the use of other devices.

In the practice of my improvement I propose to use several converters to each converter-frame, in order that a fresh charge of metal in a converter may always be ready while the charge in the preceding converter is being treated, and also to allow the withdrawal of one or more of the converters to a separate 115 shop for relining or repairs without disturbing the operation of the plant. The converters should all be of a standard form and size, so far as the trunnions are concerned, in order that they may fit readily into the trunnion-bearings in the converter-frames; but they 120 may be made of different internal capacity, if desired.

In the operation of my improvement a converter is placed on one of the trucks and conveyed to the blast-furnace. The metal is charged into the converter and the cap is placed over its mouth. The converter is then conveyed and run into the converting-house, mouth foremost, until the wheels of the truck 130 are stopped against the turned-up rails at the end of the adjustable track-section, which stop

the converter in the proper place for lowering it into its trunnion-bearings. The end of the adjustable track-section is then lowered by means of the hydraulic ram C. The trunnions 5 of the converter become deposited in their bearings in the converter-frame, and the gear-wheel on the end of one of the trunnions meshes into a rack, so that a connection is formed for moving the converter on its trunnions in the ordinary manner. The blast-connections are then made by forcing the blast-nozzle into the blast-opening in the converter. The truck is withdrawn and the converter is turned up and the charge is treated in the 10 usual manner. When the converter is emptied the blast-nozzle is drawn back from the trunnion, the truck is run under the converter, and it is withdrawn to the furnace to receive a fresh charge. In the meantime another converter held in waiting is run in, placed in position, and a second bath of metal is treated, and in this manner a series of converters containing fresh charges are blown, so that the 15 converting department may be kept working at as high rate of production as the facilities 20 for handling the molds and ingots in the casting-pit will allow.

The time required to conduct the preceding operation will be about as follows: taking a 25 loaded converter from the outside of the converter-building and depositing it into position ready for work, three minutes; blowing, seventeen minutes; deoxygenizing and emptying the metal into the ladle, four minutes; making 30 a total of twenty-four minutes for treating the heat and placing the converter into position, and by allowing three minutes for the withdrawal of the converter and three minutes more for defective practice it will be seen that 35 thirty minutes should be ample time for each heat by this method when the blast-furnaces have sufficient capacity to supply metal to keep the converters ready. This practice will be capable of giving an output of three hundred 40 and fifty tons with a single eight-ton converter-plant in twenty-two hours, leaving two hours per day for repairs, or seven hundred tons with a two eight-ton converter-plant, the output 45 possible being nearly double the practice in this country.

In the initial practice of my invention it is desirable that the converters should be first placed in position and heated in the usual manner, and that the caps should be placed 50 over their mouths after they have been charged at the blast-furnace; but after the first blow they will retain sufficient heat for the succeeding charge.

In the application of my method to the 55 manufacture of ingot iron and steel by the basic process, I line the converters with lime, successively charge them at the blast-furnaces and run them into position, add the basic additions and adjust the blast-connections, and 60 treat the charges in the usual manner. In this operation it will be found that less lime

additions will be required, the linings will last longer, and the metal will work hotter and a better product will be secured than in the usual practice. These results are due to the following facts: First, when the metal is run into pigs it takes up a considerable amount of silica from the molding-sand, and when remelted in the cupola it takes up a portion of silica from the ash of the fuel and from the silicious linings of the cupola and of the troughs which conduct it into the converter. A considerable portion of this silica enters with the metal into the converter and is destructive to the lime lining, requires the presence of larger basic 75 additions for its neutralization; but in working the metal direct these evils are avoided. Secondly, in remelting pig metal from forty to fifty per cent. of the carbon and a considerable proportion of the manganese are lost by oxidation; but in the direct process all of the carbon and manganese are carried over and develop their full amount of caloric, and maintain the metal in a highly-fluid state during 80 its treatment in the converter.

The advantages of my invention are, first, the output in the practice of the basic process may be increased to a point equal or above that of the best acid-plants now running; second, the necessity of stopping for relining and 90 repairing the converter and converter-bottoms, both by the basic and acid processes, is avoided by the use of my invention; third, it will render the basic process more thorough and efficient and the lime linings will last longer; 95 and less basic additions will be required; fourth, it dispenses with the necessity of a casting-house at the blast-furnace, the cost of molding-sand, the labor of molding, casting, and ramming, and also saves the labor of 100 breaking the pigs from the sows and loading them on the cars; fifth, it saves the scrap, which would be lost in molding and casting at the furnace, and it also saves the loss of metal which would take place in remelting; sixth, 105 it dispenses with the cost of constructing and maintaining the cupolas, cupola-hoists, and house, economizes their room and the cost of fuel and labor for remelting; seventh, by working the metal direct its quality may be determined within thirty minutes by a sample taken 110 direct at the blast-furnace from the converter, and the furnace practice can be regulated quickly to produce uniformly the grade of metal desired for converting; eighth, the converters may be easily conveyed to a shop specially adapted for repairing and relining; 115 ninth, as it dispenses with remelting, the furnace may be run so as to produce a metal low in silicon, as the full amount of carbon and 120 manganese may be relied upon as caloric-producing agents when the metal is blown.

In the practice of my invention two or more acid-lined converters may be charged at the blast-furnace at the same time, as the metal 125 will remain sufficiently fluid for bessemerizing for a considerable length of time after it is

charged, and the first converter charged will be blown before the third converter is filled at the furnace.

What I claim, and desire to secure by Letters Patent, is—

1. The method herein described for producing Bessemer ingot iron and steel, which consists in charging the molten metal direct from the blast-furnace into a portable converter, running the converter into the converting-house, depositing it on its trunnion-bearings, forming the blast-connections, and then treating the metal in the usual manner, substantially as and for the purpose herein set forth.
2. The method herein set forth, which consists in charging a series of converters at the blast-furnace, removing them to the converting-house, and successively depositing them in the trunnion-bearings of the converter-frames, forming the blast-connections and treating each successive charge in the usual manner, and then conveying the converters, as soon as emptied, from the converting-house, substantially as and for the purpose described.
3. In a Bessemer plant, the combination, with a converter-frame and detachable converter, of a vertically-adjustable track-section arranged below the same, substantially as and for the purpose specified.
4. In a Bessemer plant, a railway-track having an adjustable section pivoted at the rear of and terminating at the front of the converter-frame, whereby the front end of the sec-

tion may be raised or lowered by any suitable lifting and lowering device, substantially as and for the purpose specified.

5. The combination of a section of adjustable railway-track, pivoted at the rear of and terminating at the front of the converter-frame, with a hydraulic ram provided with trunnions resting in suitable pillow-blocks, constructed and arranged to operate substantially as and for the purpose herein set forth.

6. The apparatus herein described for connecting and disconnecting the blast-conduit with a converter-trunnion, which consists of a closed sleeve having a lateral opening, and of a hollow blast-nozzle incased within the sleeve, and also having a lateral opening, and capable of longitudinal movement within the sleeve, whereby the blast is automatically let into the trunnion when the connection is made and cut off when the nozzle is withdrawn, substantially as and for the purpose specified.

7. A converter car or truck having a frame of cast or wrought iron to conform with the shape of the back of the converter, whereby the converter is held securely and the blast-pipe and tuyere-box are prevented from coming into contact with the frame of the truck during transportation.

JACOB REESE.
